UNITED STATES PATENT OFFICE.

JOHN A. SMITH, OF NEW BRUNSWICK, NEW JERSEY.

COMBINED FENCE-WIRE SUPPORTING AND LOCKING DEVICE.

1,201,772.

Specification of Letters Patent.

Patented Oct. 17, 1916.

Application filed October 19, 1915. Serial No. 56,672.

To all whom it may concern:

Be it known that I, JOHN A. SMITH, a citizen of the United States, residing at New Brunswick, county of Middlesex, and State of New Jersey, have invented certain new and useful Improvements in Combined Fence-Wire Supporting and Locking Devices, of which the following is a specification.

10 The general object of the invention is to adapt the supports or posts of a wire or a super-wire fence, to directly connect with the fence wires and to effectively lock these against displacement, and thereby render as 15 unnecessary the use of staples, nails and equivalent wire fastening devices. And to this end the invention resides in a sectional wire supporting element, one section of which is adapted to extend around and support 20 the fence wires against downward and outward displacement, and another section of which co-acts with the first-named section to prevent upward displacement of the wires.

25 Other objects will appear and be better understood from that embodiment of my invention of which the following is a specification, reference being had to the accompanying drawings forming part hereof, in 30 which:—

Figure 1 is a front elevation of one embodiment of the invention in use. Fig. 2 is a detail side elevation of the embodiment shown in Fig. 1 partly in section. Fig. 3 is an enlarged detail of one end portion of 35 the body. Fig. 4 is a view similar to Fig. 3 of the retaining bar. Fig. 5 is a sectional detail of a modified form of lock for the body and the retaining bar.

40 The wire supporting and locking element of this invention may be formed of any material found suitable for the purpose, as sheet metal. When formed of the last-named material, the said element is stamped or otherwise cut to the required size from 45 a metallic sheet and then operated upon by a punch press or other suitable contrivance which forms therein the devices adapted for supporting and locking the fence wires.

50 In the embodiment shown, the said element is indicated by α , and for purposes of illustration is shown as consisting of a plurality of sections, one of which is indicated by 5 and the other by 6. These sections,

respectively, will subsequently be referred to as the body and the retaining bar. The tongues or keepers 7 on body 5, are shown as being upstruck from the said body, and their upper ends are free, whereby to facilitate the introduction of the fence wires into the spaces between the body and the said tongues or keepers. On account of their resilient properties the tongues or keepers 7 have their free ends sloped inwardly or toward the body 5, and are spaced from the said body for a distance somewhat less than the diameter of the fence wires to be supported, while the base portions of the tongues bulge outwardly so as to provide intervening spaces corresponding in area and in shape approximately to the cross sectional area and contour to the fence wires. Thus it will be seen that in the act of adjusting the fence wires 8, the free ends of the tongues or keepers, upon the passing of 75 the wires 8 into the smaller portions of the said spaces, yield outwardly until the said wires are well into the larger portions of the said spaces, whereupon the tongues or keepers will, by reason of their own resiliency, resume their normal positions and by virtue of their presence, positively prevent downward or outward displacement of the wires 8, and by reason of their shape, yieldingly hold the said wires against upward 80 displacement.

The retaining bar 6 is designed to be superimposed on body 5, after the adjustment of the wires 8 to tongues or keepers 7 has been effected. The retaining bar, when 90 so positioned, bears on the portions of wires 8 which project immediately beyond the sides of tongues or keepers 7; and it will be noted that the portions of the retaining bar which bear on the wires, are bulged or 95 curved outwardly, as indicated by 9, to accommodate the wires, and further, that the said retaining bar has slots 10 which receive tongues or keepers 7. By reason of these 100 constructions the greater portion of the inner surface of the retaining bar, may bear on the adjacent surface of body 5 so that when the body and retaining bar have been secured one to the other in any of manners hereinafter to be described, they will 105 co-operate to positively prevent disengagement of the wires from the supporting element.

As shown in Fig. 1, the body and the re-

taining bar may be fastened one to the other by bolts 11 which pass through alining openings in the body and the bar, and nuts 12. Or as shown in Fig. 5, the locking of the retaining bar to the body may be effected by moving the said bar longitudinally until the portions immediately beyond the upper ends of slots 10, are behind the upper ends of the tongues or keepers 7. In 10 this position the parts may be additionally secured by suitable fastening devices, as bolts and nuts 12, arranged at the opposite end portions of the retaining bar.

When the invention is arranged as shown 15 in Fig. 1, it functions as a super-fence and thereby prohibits easy climbing of the main fence 16 or access to the ground surrounded thereby except through the prescribed entrances. It will be noted that the extended 20 lower end portion of body 5 is bent at an obtuse angle, as indicated by 17, to the portion of the body directly above, and provided with openings which receive suitable fastening devices, such as nails 18, which 25 secure it to the main fence. By reason of this construction the super-fence may be caused to extend in an inclined direction outwardly over the main fence 16 or inwardly over the inclosure, depending on 30 which face of the extension 17 is arranged in contact with the said main fence.

Although I have shown and described the invention as a super-fence and adapted for supporting barbed or rolled wire, it will 35 be understood that this is merely illustrative, it being obvious that the body 5 and retaining bar 6 may be so modified in length as to admit of their being secured to other structures than a board fence, for instance, the 40 device may be secured to a fence post and operate to secure either rolled or netted wire.

Copies of this patent may be obtained for five cents each, by addressing the "Commissioner of Patents, Washington, D. C."

What is claimed as new is:

1. In a wire fence, a combined wire supporting and locking device including a body 45 portion provided with a series of upwardly and outwardly extending resilient tongues the base portions of which are curved and extend around the fence wires, and the free end portions of which are spaced from the 50 body for a distance less than the diameter of the wires, a retaining bar superimposed on the said body and connected thereto and having openings through which the tongues extend and further having bulged portions 55 at opposite sides of the openings which aline with the curved portions of the tongues and extend around the fence wires.

2. In a wire fence, a combined wire supporting and locking device including a body 60 portion one end of which is offset and adapted for adjustment to a support, said body portion being provided with a series of upwardly and outwardly extending resilient tongues the base portions of which are 65 curved and extend around the fence wires, and the free end portions of which are spaced from the body for a distance less than the diameter of the wires, a retaining bar superimposed on the said body and connected thereto and having openings through 70 which the tongues extend and further having bulged portions at opposite sides of the openings which aline with the curved portions of the tongues and extend around the 75 fence wires.

In testimony whereof, I have signed my name to this specification in the presence of two subscribing witnesses.

JOHN A. SMITH.
